UNITED STATES PATENT OFFICE.

WILLIAM L. CHAPMAN, OF BROOKLYN, NEW YORK.

PIPE-LAYING APPARATUS.

1,220,187.

Specification of Letters Patent. Patented Mar. 27, 1917.

Application filed July 13, 1916. Serial No. 109,032.

To all whom it may concern:

Be it known that I, WILLIAM L. CHAPMAN, a citizen of the United States, and a resident of the borough of Brooklyn of the city of New York, in the State of New York, have invented an Improvement in Pipe-Laying Apparatus, of which the following is a specification.

This invention relates more particularly to the means for supporting and advancing a pipe laying apparatus in which a line of pipe, the sections of which have been fitted together at a point above and remote from where they are to be laid, the line of pipe thus formed being lowered into position by means of the apparatus. The general features of such apparatus are more particularly described and illustrated in my companion applications, Serial Nos. 109,033 and 109,034, both filed July 13, 1916.

In the accompanying drawings, I have illustrated one embodiment of the present improvements, in which—

Figure 1 is a view in side elevation of the apparatus as a whole, the improvements being applied thereto;

Fig. 2 is a detail plan view on a larger scale, showing the connections of the towing lines (to be described presently) to the scow or other support which is used to sustain the so-called "launching skid";

Fig. 3 is another detail plan view showing the lower end of the skid and the manner of attaching the towing line;

Fig. 4 is a plan view of said scow, the anchoring devices therefor being indicated in dotted lines;

Figs. 5 and 6 are respectively a front and side elevation of a sling and its supporting sheave which is used to suspend the skid from the scow; and

Figs. 7 and 8 are similar views of a modified form of sling and its pivot connection with the scow.

Referring first to Fig. 1, which shows the general view of the apparatus, it will be seen that the skid forms a curvilinear launchway for the line of pipe which is discharged from its lower end, and the sections of pipe of which are united at its upper end;

This skid is suspended from a scow or other support 1 so as to have free lateral play which is advantageous in taking care of the fluctuations caused by the rolling of the scow or any surging motion. For this purpose, it is provided near its upper end

with a supporting yoke consisting of a cross bar 50 and a sling 51, the bar being secured to the skid by means of universal joints 52 and the sling being passed over an eccentrically pivoted sheave 53 (Figs. 5 and 6). This sheave forms a part of a frame 54 which is rigidly secured to the scow 1 and overhangs the forward end of the scow so that the sling depending therefrom conveniently supports the upper end of the skid in such way the latter is free to sway in any direction without danger of coming in contact with the scow.

When the boat rolls, the eccentric pivoting of the sheave tends to cause the pivot to turn in the sheave without affecting the skid at all; and whenever, from any cause, the skid itself tends to move laterally in respect to the scow, the eccentric pivoting of the sheave tends immediately to bring it back again to center.

In Figs. 7 and 8, instead of having an eccentric sheave which the sling passes over, as around a pulley, there is provided a collar 55 having a pair of projecting lugs 56 which are engaged respectively by cables 57 which thus connect the rod 50 with said collar. This alternative form (the form shown in Figs. 7 and 8) was used at the commencement of operations in the apparatus at the Narrows in New York harbor, to which I have alluded in both of the above identified companion applications filed herewith; but it was later superseded in said apparatus by the form shown in Figs. 4 and 5 which I prefer to use, owing to the advantage which the eccentric sheave gives in minimizing the motion of the skid.

For the purpose of advancing the skid, it was explained in my companion application Serial No. 109,034, above identified that the rear anchor lines were loosened and the forward anchor lines drawn upon. This of course would advance the scow, the skid being drawn along with the scow through the medium of a towing line or lines. In accordance with the present invention, the towing line 19 is secured at or near the lower or submerged end of the skid and its ends are passed up and around the front of the scow over sheaves 20 journaled upon the rigid frame 54. For the purpose of securing it to the lower end of the skid and equalizing the draft upon each end of the line so that the pull will be evenly distributed between both sides of the skid, a sheave 58 is

provided through which the towing line 19 passes, and said sheave is connected to the skid by a sling 59, the ends of which are fastened on each side near the bottom of the 5 skid. The ends of the towing rope 19 pass backwardly along the frame 54 to yielding connections 21 whereby they are secured to the frame. The purpose of these yielding connections is to keep the towing rope taut 10 at all times and prevent any impact caused by the surging of the scow; for in addition to its function of towing, the rope 19 acts at all times to keep the skid in its true relation with respect to the scow. When the 15 scow is advanced by pulling on the forward anchor lines and loosening the rear anchor lines, the towing line hauls the skid forward by drawing on its lower end. In this way, the skid is strained less than in the case 20 where the skid is pulled at its forward end alone.

In addition to the towing line 19, there are provided towing lines 60. Normally, this additional pair of towing lines is allowed 25 to remain slack, in which case they perform no function whatever. The slack, however, is very slight so that in case the towing line 19 should break, the additional towing lines 60, or one of them as the case 30 may be, comes immediately into play and may be used until a repair can be made of the original towing line or lines. The additional towing lines have no yielding connections but are rigidly secured, as indicated, 35 to the skid on the one hand, and the scow on the other.

It will be unnecessary to refer to the operation of the apparatus beyond what has just been described. Reference should be 40 had to my companion applications for a completer description of the entire apparatus.

I claim as my invention:

1. In a pipe laying apparatus, the combination with a support, of a skid for sliding the pipe into position, suspended from the support with freedom for lateral play, and means to suspend said skid from said support including a sling having a pivotal connection with said support.

2. In a pipe laying apparatus, the combination with a support, of a skid for sliding the pipe into position, suspended from the support with freedom for lateral play, and means to suspend said skid from said support including a sling and an eccentric sheave pivoted to said support and over which the sling passes.

3. In a pipe laying apparatus, the combination of a scow, a supporting frame secured thereto and overhanging the scow, a

skid for sliding the pipe into position, an eccentric sheave pivoted upon the frame, and a sling secured to the upper end of the skid and passing over the sheave.

65

4. In a pipe laying apparatus, the combination with a support, of a skid for sliding the pipe into position, secured at its upper end to the support, and towing wires to advance the skid, said wires being secured to the support adjacent the point of attachment of the skid and being secured at or near the lower end of the skid and extending substantially parallel to said skid whereby the skid is advanced by drawing on its lower 75 end.

5. In a pipe laying apparatus, the combination with a support, of a skid for sliding the pipe into position secured at its upper end to the support, means for preventing 80 the sidewise roll of the scow being communicated to said skid, and towing wires to advance the skid secured at or near the lower end thereof and passing forward to a point of attachment on the support near the upper 85 end of the skid.

6. In a pipe laying apparatus, the combination with a support, of a skid for sliding the pipe into position, means to secure the upper end of the skid to the support, a towing line secured to the lower end of the skid, a pair of sheaves on the support around which the ends of the towing line are passed, and independent yielding connections on the support to which said ends of the towing line 95 are secured after passing over the sheaves.

7. In a pipe laying apparatus, the combination with a support, of a skid for sliding the pipe into position, secured at its upper end to the support, a towing wire to advance 100 the skid secured at or near the lower end thereof and yieldingly connected to the support so as to remain substantially taut at all times, and an additional towing wire connected to the lower end of the skid and to the 105 support so as to remain normally slack.

8. In a pipe laying apparatus, the combination with a support, of a skid for sliding the pipe into position, secured at its upper end to the support, towing wires to advance 110 the skid secured at or near the lower end thereof and extending substantially parallel to said skid, whereby the skid is advanced by drawing on its lower end, and yielding connections between the skid and the support 115 whereby said towing wires act as well to maintain the lower end of the skid in its true position at all times.

In testimony whereof, I have signed my name to this specification this tenth day of 120 July, 1916.

WILLIAM L. CHAPMAN.
